CHAIR OR THE LIKE

George E. Schaefer and Robert I. Anderson, Muskegon, Mich., and Richard G. Reineman, Covina, Calif., assignors to The Brunswick-Balke-Collender Company, Chicago, Ill., a corporation of Delaware

Filed May 22, 1958, Ser. No. 51,020

Term of patent 14 years

(Cl. D15—1)

Fig. 1 is a perspective view of a chair or the like showing our new design;

Fig. 2 is a side elevational view thereof;

Fig. 3 is a front elevational view thereof; and
Fig. 4 is a top plan view thereof.

The essential feature of our design resides in the combination on the chair disclosed of the particular side bracket of the configuration shown together with the angled short rear leg and the angled longer front leg on each side of the seat portion substantially as shown.

The rear and bottom of the seat portion are conventional and an optional shelf is shown in broken lines below the seat.

We claim:

The ornamental design for a chair or the like, as shown and described.
